US00D654869S

(12) **United States Design Patent**
Konz

(10) **Patent No.:** **US D654,869 S**
(45) **Date of Patent:** **** Feb. 28, 2012**

(54) **ELECTRONIC COMPONENT**

(75) Inventor: **Oliver Konz**, Ilshofen (DE)

(73) Assignee: **Wuerth Elektronik eiSos GmbH & Co. KG**, Waldenburg (DE)

(**) Term: **14 Years**

(21) Appl. No.: **29/390,194**

(22) Filed: **Apr. 21, 2011**

(30) **Foreign Application Priority Data**

Oct. 26, 2010 (EM) 001241574-0002

(51) **LOC (9) Cl.** **13-02**

(52) **U.S. Cl.** **D13/110**

(57) **CLAIM**

The ornamental design for an electronic component, as shown and described.

DESCRIPTION

FIG. 1 is a top plan view of the electronic component;
FIG. 2 is a front elevation view thereof;
FIG. 3 is a rear elevation view thereof;
FIG. 4 is a bottom plan view thereof;
FIG. 5 is a side elevation view thereof (the opposite side being a mirror image);
FIG. 6 is a (front) side perspective view thereof; and,
FIG. 7 is a (rear) side perspective view thereof.
The broken lines shown represent unclaimed subject matter and form no part of the claimed design.
